WINDOW

Harris E. Vaughn, Reno, Nev.

Application March 16, 1948, Serial No. 15,169

3 Claims. (Cl. 160—187)

1

This invention is a two part window comprising upper and lower sash which are linked together by links, the links being pivoted to the stiles of the two sash at points adjacent the meeting rails thereof.

Both the upper and lower sash can swing inwardly; the upper sash swings on a horizontal axis at about the level of its upper-rail, while the lower sash swings about a horizontal axis at about the level of its lower rail.

Both upper and lower sash engage with the side jambs of the window frame in which they are mounted, on these horizontal pivotal axes, and it is an important object and feature of the invention that both upper and lower sash may be readily and quickly removed from the window frame simply by disengagement of these two pivotal axes from the side jambs of the window.

Each of the two sash may be positioned at a desired level independently of the other sash. This feature, in combination with the link connection adjacent the meeting rails of the two sash, enables the two sash to be positioned in various relative positions, such as the following:

A. The upper sash is slightly lowered and in a vertical plane, with the lower sash inclined outwardly.

B. The upper sash slightly lowered and inclined outwardly with the lower sash in a vertical plane.

C. Both sash at an angle inwardly, one of the sash being lowered or raised from normal position.

D. Upper sash at an angle inwardly, with the lower sash vertical and raised above its normal position.

E. Both sash in closed position, in the same vertical plane.

The two sash, when the window is closed, are in the same vertical plane, the meeting rails fitting together with a rabbeted construction. With this arrangement one sash, preferably the lower sash, which has a shoulder that overlaps the other, is provided with simple pivoted latches engageable with the side jambs, so that these latches hold both sash in the closed position.

In relatively small installations, where the sashes are not heavy, no counter-balancing springs or weights are necessary. However, where heavy sash are involved, counter-weights or springs may be provided for facilitating the opening and closing movements of the window.

The invention will be further described in connection with the accompanying drawings wherein:

Fig. 1 is a perspective view showing the upper and lower sash separated from the window frame.

Figs. 2, 3, 4, 5 and 6 are diagrammatic views illustrating various relative positions that may be assumed by the upper and lower sash.

Fig. 7 is an enlarged horizontal section, taken on the line 7—7 of Fig. 2, modified to show the use of weatherstripping.

Fig. 8 is an enlarged edge view of a friction grip device that may be used, if desired.

Fig. 9 is a view of a detail of the friction grip device.

Fig. 10 is a side view of the friction grip device.

Referring now to these drawings, the window of this invention comprises a lower sash indicated generally at 2, comprising stiles 4 and 6, upper rail 8 and lower rail 10. The upper sash indicated generally at 12, comprises stiles 14 and 16, upper rail 18 and lower rail 20.

The lower rail 10 of the lower sash is provided in its bottom edge with a pivot rod 22, the ends of which project to the right and left beyond the outer edges of the stiles 4 and 6, to form pivot pins.

The upper rail 18 of the upper sash is provided in its top edge with a similar pivotal rod 24, the ends of which project beyond the outer edges of stiles 14 and 16 to form pivot pins.

Coming now to an important feature of the invention, the two sash 2 and 12 are linked together near their meeting rails by means of links 26, pivoted respectively to the stiles at 28 and 30. These links 26 are of relatively thin sheet metal.

The meeting rails 8 and 20 are rabbeted forming shoulders 32 and 33. The shoulder 32 of rail 8 overlaps shoulder 33 of rail 20, so that in closed position the two rails and also the two sash 2 and 14 are in the same plane.

The upper rail 8 of the lower sash is provided with latches 34 of any desired type, conveniently latches turning on a horizontal axis and engaging in recesses 35. These latches hold both sash closed, on account of the overlapping shoulders 32 and 33.

The two part window just described is mounted in a window frame comprising a sill 40, side jambs 42 and 44, and head jamb 46, the side jambs and head jamb being provided with the usual blind stop 48.

Just within blind stop 48, the head jamb is provided with a horizontal groove 50 and in the same plane with 50, the side jambs are provided with vertical grooves 52 extending for the full

length of the jambs. The side jambs are also provided with downwardly and inwardly inclined notches or sockets 54. The side jambs are also provided with horizontal grooves 56 for accommodating the projecting pivots 22 and 24, for use in putting the window in the frame or removing it therefrom.

The sill 40 is provided with a horizontal groove 57, registering at its ends with vertical grooves 52, for accommodating pivot rod 22.

To assemble the window, the projecting ends of pivot 22 is slid into slots 56 and then the sash is dropped to the sill, the pivots sliding in grooves 52. Then the ends of upper pivot 24 are passed through slots 56 and the upper sash moved all the way up as far as it will go; then the lower sash is moved inwardly into the same plane, with the upper sash, so that the rails overlap, and both sash are held by turning latches 34 which engage in recesses or keepers 35 in the side jamb. The window may be readily removed simply by reversing these operations.

With the construction described, the two sash may take various relative positions for example, as follows:

As shown in Fig. 3, the upper sash is lowered slightly and held by pivots 24 in one pair of notches 54, while the lower sash is angled inwardly, to deflect incoming air upwardly. Some air circulation would also take place over the top of the upper sash. The upper sash could, if desired, remain all the way up, with the lower sash angled inwardly.

In Fig. 4, both sash are angled inwardly, one or both, if desired, being moved up or down from the sill or top jamb. Ventilation would mainly be at the top of the window.

In Fig. 5, the lower sash remains in its lowered vertical position, the upper sash being nearly all the way down. Ventilation would mainly be at the top, with some air deflection downwardly.

In Fig. 6, the lower sash is raised and held by pivots 22 in one pair of notches 54, while the upper sash is angled inwardly to deflect air downwardly.

An important feature in achieving the above described positions is the connecting link 26, whereby either meeting rail of either sash may be positioned well outwardly, or well inwardly, with respect to the adjacent rail of the other sash, for deflecting incoming air either upwardly or downwardly.

The fact that either upper or lower sash may be positioned at various levels, in cooperation with the connecting pivotal link 26, provides a two part window which may be positioned in many positions, where the upper sash is all the way up or part way down, or the lower sash is all the way down or part way up, and in any of these positions either or both windows may be angled outwardly into the room, with either meeting rail outwardly or overlapping the other meeting rail.

Furthermore, as already mentioned, the window may be very quickly assembled and disassembled. The construction is relatively simple and involves a minimum of relatively expensive metallic fittings.

As already noted, counterweights or springs may be provided for heavy sash, if desired, as is well understood in this art.

In most instances, the two sash will naturally remain in the various positions in which they may be placed. However, in order to hold the two sash in any desired adjusted position, one

or two friction operated devices may be associated with each connecting link 26. These friction devices, shown in Figs. 8, 9 and 10, impose enough force to hold the two sash in any position in which they may be placed, but this frictional force may be readily overcome manually to move the sash to other positions, the friction holding the sash in such new position.

Referring now to Figs. 8, 9 and 10, one or both ends of link 26', corresponding to link 26, is provided with a thickened head 60, radially serrated or roughened, on one side, as at 62. The serrations of heads 60 engage similar serrations 64 in a head 66, spring pressed by spring 67 against head 60. The force exerted by the springs 67 may be varied in any way desired. Head 66 is locked against rotary movement and is mounted for movement, against spring 67, in a housing 68 recessed into the stiles of the two sash. For lighter windows, one such friction grip device may be used with each link 26'; for heavier windows, two may be used with each link. Weatherstripping may be used if desired. As shown at the left of Fig. 7, weatherstripping 70, of felt or the like, may be secured in recesses 72 in the blind stop 48, all the way around, the felt being positioned so as to be compressed by and so to fit tightly against, the stiles and rails of the window. As shown at the right of Fig. 7, weatherstripping 74, of felt or the like, is secured to the blind stop so as to be compressed by the stiles and rails to make a tight joint. The weatherstripping 72 or 74 may be sheathed with a thin protecting strip 76 of metal or the like.

While the invention has been described in some detail, it should be understood that the invention is not to be limited to these details, but may be carried out in other ways.

I claim as my invention:

1. A window, comprising a frame having vertical grooves in the side jambs thereof, and having sockets opening into said grooves, an upper sash, a horizontal pivot carried by the upper rail of the upper sash, the ends of which pivot are positioned to engage in said grooves and sockets, a lower sash, a horizontal pivot carried by the lower rail of the lower sash, the ends of which pivot are positioned to engage in said grooves, and a pair of links connecting the two sash, each link being pivoted to adjacent stiles of the upper and lower sash, whereby the upper sash is positionable at different levels in a vertical or inclined plane, each side jamb also being provided with a lateral groove, opening into the vertical grooves therein, for accommodating the ends of said horizontal pivots in the assembling and disassembling of the window.

2. A window, comprising a frame having vertical grooves in the side jambs thereof, and having sockets opening into said grooves, an upper sash, a horizontal pivot carried by the upper rail of the upper sash, the ends of which pivot are positioned to engage in said grooves and sockets, a lower sash, a horizontal pivot carried by the lower rail of the lower sash, the ends of which pivot are positioned to engage in said grooves, and a pair of links connecting the two sash, each link being pivoted to adjacent stiles of the upper and lower sash, near the meeting rails thereof, whereby the upper sash is positionable at different levels in a vertical or inclined plane, each of said links having frictionally-operated gripping means cooperating therewith for holding the links and the sash connected therewith, in desired adjusted position.

3. A window, comprising a frame having vertical grooves in the side jambs thereof, and having sockets opening into said grooves, an upper sash, a horizontal pivot carried by the upper rail of the upper sash, the ends of which pivot are positioned to engage in said grooves and sockets, a lower sash, a horizontal pivot carried by the lower rail of the lower sash, the ends of which pivot are positioned to engage in said grooves, and in said sockets, and a pair of links connecting the two sash, each link being pivoted to adjacent stiles of the upper and lower sash, near the meeting rails thereof, whereby each sash is positionable at different levels in a vertical or inclined plane, each of said links having frictionally-oper-

ated gripping means cooperating therewith for holding the links and the sash connected therewith, in desired adjusted position.
